UNITED STATES PATENT OFFICE.

WILLIAM A. P. BICKNELL, OF NEW YORK, N. Y., ASSIGNOR TO DAUPHIN S. HINES, WILLIAM A. PERRY, AND CHARLES C. WORTHINGTON.

STEAM-ACTUATED VALVE.

SPECIFICATION forming part of Letters Patent No. 320,212, dated June 16, 1885.

Application filed November 3, 1884. (No model.)

To all whom it may concern:

Be it known that I, WILLIAM A. P. BICKNELL, a citizen of the United States, residing at New York, county of New York, and State 5 of New York, have invented certain new and useful Improvements in Steam-Actuated Valves for Direct-Acting Engines, fully described and represented in the following specification and the accompanying drawings, forming a part of the same.

This invention relates generally to that class of engines which are known as "direct-acting"—that is to say, those engines in which the piston-rod acts upon the load directly and not 15 through the medium of a crank.

The invention relates more particularly to the means by which the induction and exhaust valve is operated to admit and exhaust the steam to and from the cylinder.

20 In this class of engines no fly-wheel or other heavy moving part is employed to distribute and equalize the power, and the moving parts of the engine are usually made so light as to acquire but little momentum during the stroke. 25 This being the case, it has been found impossible in practice to operate the induction and exhaust valve directly from the piston-rod of the engine in the manner common in other classes of engines, because when the valve has 30 been moved to its center, or into such position as to shut off the further ingress of steam to the cylinder behind the advancing piston, the little momentum which the moving parts have will not be sufficient to cause the piston to advance so as to complete the stroke of the valve, and thus the engine will be brought to rest before the valve can be moved sufficiently far to open the induction-port and admit steam in front of the piston to start it upon its 35 return-stroke. This fact had made it necessary in this class of engines to provide some means by which the valve can be operated, or at least made to complete its stroke, independently of the movement of the main piston 40 and piston-rod. It is to an apparatus for this purpose that the present invention particularly relates, it being the object of the invention to provide means by which, after the valve has been carried through a part of its stroke by 45 the movement of the main piston and piston-rod, it is made to complete its stroke inde-

pendently of the movement of these parts. It is also the object of the invention to provide means for this purpose which shall be positive in its action, not liable to be rendered 55 inoperative by wear or leakage, and which shall at the same time give the best distribution of the steam to secure a smooth and quiet action of the engine.

As a full knowledge of the invention and 60 of its mode of operation can only be imparted by a detailed description of the apparatus in which it is embodied, a further preliminary description will not be given; but the apparatus will now be described in detail, reference being had to the accompanying drawings, 65 in which—

Figure 1 is a plan view of a direct-acting engine provided with a valve-operating mechanism embodying the present invention, the 70 cover of the steam-chest being removed. Fig. 2 is a cross section of the same, taken upon the line *xx* of Figs. 1 and 3. Fig. 3 is a longitudinal section of the same, taken upon the line *vv* of Figs. 1 and 2. Fig. 4 is a longitudinal section upon an enlarged scale taken upon the line *zz* of Fig. 2; and Fig. 5 is a similar view showing the parts in a different position.

Referring to said figures, it is to be understood that the engine there shown as embodying the invention consists of a steam-power cylinder, 100, having the usual piston, 99, and piston-rod 98, the latter being arranged to act directly upon the pump-plunger or other 80 load (not shown) which the engine is to move. The cylinder 100 is provided with the usual steam-chest, 97, having an opening, 96, through which the steam is admitted from the boiler or other sources of supply, and with an ordinary **D** valve, 95, which controls the induction and exhaust ports 10 11, and exhaust-outlet 12 of the cylinder in the usual manner.

The valve-rod 94 enters the steam-chest 97 95 through a stuffing-box in the usual manner, and is operated from the piston-rod 98 through any suitable form of connections, as the cross-head 90, link 91, lever 92, and link 93. The rod 94, instead of being connected directly to the valve 95, is connected to a yoke, 50, which passes around the valve, and is arranged to

move freely back and forth upon shoulders or ledges 13, formed upon the sides of the steam-chest. The yoke 50 is of such length as to afford considerable lost motion between it and the valve, so that during the first part of the stroke of the piston 99 the yoke will move idly without giving any movement to the valve, and will only commence to move the valve as the piston nears the end of its stroke.

10 Mounted upon the top of the valve is a small auxiliary cylinder, 89, which may be made integral with the valve or secured thereto, and which is provided with a piston, 14, the rod 15 of which passes through the end of the cylinder and is secured to the end of the chest 97. The attachment of the rod 15 to the chest may be effected in any convenient manner, but the rod will preferably be attached in the manner shown in the present case, so that when the top 88 of the chest is removed the valve 95, including the auxiliary cylinder 89 and its piston and piston-rod, can be readily lifted out of the chest.

The cylinder 89 is provided at its opposite ends with induction and exhaust ports 3 4, which pass laterally and open upward through the face of a narrow shoulder or projection, 17, formed on the side of the valve 95, and upon which is arranged a small B-valve, 18, which is slightly greater in length than the valve 95. The shoulder 17, which forms a seat for the valve 18, is provided just outside the ports 3 4 with vertical ducts or ports 5 6, which open downward through the lower face of the valve 95 in such position that as the valve is moved back and forth they are brought into communication respectively with two small ducts or ports, 1 2, which extend from the face of the seat 16, upon which the valve 95 reciprocates to its ends so as to open into the chest 97.

The valve 95 is also provided with a third vertical duct or port, 7, located midway between the ports 5 6 and in line therewith, which opens downward into a channel, 8, formed in the valve-seat 16, and is provided with a lateral port, 9, which opens into the cavity 19 of the valve.

The valve 18 is held in position upon its seat by means of a bearing-piece, 20, which is secured to the side of the valve, and its stroke in each direction is limited or controlled by means of projections 40, formed upon its upper side, which engage with this bearing-piece 20.

The operation of the apparatus just described is as follows: Assuming the engine to be in motion and the piston 99 to have commenced its stroke from the right toward the 60 left-hand end of the cylinder 100, as it proceeds upon its stroke in this direction the lever 92 will move the valve-rod 94 and the yoke 50 slowly toward the right, and this will continue until the piston has arrived at about the 65 middle of its stroke, at which time the yoke 50 will come into contact with the projecting

end of the valve 18 and move said valve from the position shown by dotted lines in Fig. 5 to the position shown by full lines in Figs. 4 and 5, thereby opening communication between the ports 4 6. As the piston 99 continues its stroke from this point, the yoke 50 will come into contact with the valve 95 and commence to move said valve forward, so as to gradually close the port 11 and cut off the admission of steam to the cylinder, and this will continue until the valve arrives in the position shown in Figs. 3 and 4, in which position it will cut off the further admission of steam to the cylinder in front of the piston, so that the latter will be arrested. The lever 92 is so proportioned, however, that when the valve has been moved to this position the piston 99 will have arrived at the end of its stroke, as also shown in Fig. 3. As soon, however, as the valve arrives in the position just stated, the port 6 will be brought into communication with the port 2, as shown in Fig. 4, so that the live steam from the chest 97 will pass through the ports 2 6 4 into the right-hand end of the cylinder 89. The piston 14 90 of this cylinder being held stationary by its rod 15 the steam thus admitted will act upon the end of the cylinder, so as to force it, and with it the valve 95, over to the position shown in Fig. 5, and thus complete the stroke of the 95 valve and open the port 10 to admit steam in front of the piston 99 to start it upon its return-stroke, and at the same time open the port 11 to admit the steam already upon the opposite side of the piston to be exhausted 100 through said port and the outlet 12. As the piston proceeds upon its return-stroke the yoke 50 will be moved in the opposite direction until it is brought into contact with the opposite end of the valve 18, when it will shift said 105 valve from the position shown in Figs. 4 and 5 back to that shown by dotted lines in Fig. 5, so as to close the port 6 and open communication between the ports 4 7, and thus permit the steam in the cylinder 89 to be exhausted 110 through the port 9 into the exhaust-outlet 12, and at the same time open communication between the ports 3 5. As the piston 99 advances and completes its stroke, the valve 95 will be moved back to its center, which will 115 bring the port 5 into communication with the port 1, so as to admit steam through the ports 1 5 3 into the opposite end of the cylinder 89, which will operate in the manner already stated to complete the stroke of the valve in this direction and again reverse the movement of the piston 99, and so the operation will continue to be repeated, the valve 95 being moved to its center at each stroke by the piston 99, and then from its center on to complete its stroke 120 by the action of the steam in the auxiliary cylinder 89.

If at any time the speed of the engine should be accelerated to such an extent that the piston 99 should not be arrested as soon as the 130 valve 95 arrives at its center the further movement of the piston would carry the valve past

the center, and thus at once open the induction-port leading to the front of the piston and admit live steam to that end of the cylinder, so as to cushion the piston and prevent it from 5 coming into contact with the cylinder head.

It will be observed that sufficient space is left between the ports 3 4 and the heads of the cylinder 89, so that the steam confined in this space after the piston 14 has covered the ports 10 will form a sufficient cushion to prevent the ends of the cylinder from coming into contact with the piston.

The ports 1 2 will preferably be located as shown, so that they will be out of communication with the ports 5 6 when the valve is at the limit of its stroke in either direction, thus cutting off the steam from the cylinder 89 and preventing loss from leakage past the piston 14 while the piston 99 is making its stroke. 20 These ports may, if desired, be provided with suitable cocks or valves, as 21, by which the amount of steam allowed to pass through these ports can be regulated, thus providing an efficient means for timing the movement of the 25 valve. By this means the movement of the valve can be so delayed that the piston 99 will be made to have a pause at the end of each stroke.

If the valve 18 should become worn, or for 30 any reason should fit imperfectly, so as to permit the steam to leak past it and enter the cylinder 89 before the valve has been moved into position to open communication between the ports 1 5 or 2 6, such steam will 35 find an escape through port 5 or 6, channel 8, and the ports 7 and 9 to the exhaust-outlet 12, and thus prevent a premature movement of the valve.

It will readily be seen that the apparatus 40 just described is simple in its construction; not liable to get out of order; that the parts are all readily accessible in case that repairs are needed, and that it can be produced at a comparatively small cost. The piston 14 is 45 much less inclined to get out of line or stick than the double-chest plungers commonly employed to throw the valves of this class of engine, and requires less machine-work. It also requires much less material, and can 50 therefore be made, if desired, of brass or other suitable metal that will not rust to the cylinder. The loss from leakage is also much less than in the ordinary construction, as the steam can be cut off from the cylinder 89 after 55 the valve has been reversed, as already explained.

I do not limit myself to the precise construction of devices herein shown for operating the valve-rod 94, as it will readily be seen 60 that almost any of the ordinary devices for this purpose might be employed in the present case without departing from the spirit of the invention. Thus, by making the valve of **B** instead of **D** form, a simple tappet movement might be employed for operating the rod 94, and in such case the lost motion between

the valve and the yoke 50 would be proportionately reduced; but such devices would not be as desirable as the lever movement herein shown, because the valve could not in 70 that case be closed gradually at the end of the stroke of the piston 99, and the engine would consequently not have the advantage of the corresponding gradual reduction in speed at the end of the stroke. 75

Neither do I limit myself to the precise arrangement herein shown of the ports for admitting and exhausting the steam to and from the auxiliary cylinder 89, as the arrangement of these ports may be varied considerably without departing from the invention. 80

What I claim is—

1. In a direct-acting engine, the combination, with the main cylinder, piston, and piston-rod, of the main valve provided with or carrying an auxiliary cylinder having a stationary piston and piston-rod, and suitable ports for admitting and exhausting steam, the valve 18, arranged to control the admission and 85 exhaust of the steam to and from the auxiliary cylinder, and connections, substantially as described, by which the valve 18 is moved through its whole stroke and the main valve through a part of its stroke by the 90 main piston, the whole being arranged and operating substantially as described. 95

2. In a direct-acting engine, the combination, with the main valve 95, carrying the auxiliary cylinder 89, having the stationary 100 piston and piston-rod, and suitable ports for the admission and exhaust of the steam to and from said auxiliary cylinder, which ports are only brought into communication so as to admit the steam after the valve 95 has been 105 moved through a part of its stroke, the valve 18 for controlling the exhaust, and connections, as the yoke 50, valve-rod 94, &c., by which the valve 18 will be moved to open the exhaust of the auxiliary cylinder 89 before the 110 valve 95 commences its stroke, substantially as described.

3. In a direct-acting engine, the combination, with the main cylinder, piston, and piston-rod, of the main valve provided with or 115 carrying an auxiliary cylinder having a stationary piston and piston-rod, and suitable ports for admitting and exhausting steam, the valve 18, for controlling the admission and exhaust of the steam to and from the auxiliary cylinder, connections for operating the 120 valve 18 from the main piston, and the channel 8, arranged to communicate with the ports 5, 6, and 7, substantially as described.

4. In a direct-acting engine, the combination, with the main cylinder, piston, and piston-rod, of the main valve provided with or carrying an auxiliary cylinder having a stationary piston and piston-rod, the valve 18, arranged to control the admission and 125 exhaust of the steam to and from the auxiliary cylinder, and suitable ports for the admis- 130

sion and exhaust of the steam, which are so arranged that after the valve 18 has been moved through its whole stroke and opened the exhaust the main valve must then be 5 moved through a part of its stroke before the admission of the steam to the auxiliary cylinder can take place, all substantially as described.

In testimony whereof I have hereunto set my hand in the presence of two subscribing 10 witnesses.

W. A. P. BICKNELL.
